BOX BLANK FORMING MACHINE

George S. Sillars, Beverly, Mass., assignor to
 Hoague-Sprague Corporation, Lynn, Mass., a
 corporation of Massachusetts

Application March 1, 1949, Serial No. 79,052

7 Claims. (Cl. 93—58.3)

1

This invention relates to machines for producing box blanks and is illustrated herein as embodied in a machine for forming box blanks of the type having a body portion, side wings, end wings, corner laps and end wing extensions designed when set up to form a complete double end walled box such as is used in the packaging of shoes and the like.

In the manufacture of such blanks for shoe boxes, varying demands of shoe manufacturers necessitate the production of box blanks of different dimensions to form boxes of different lengths, widths and heights. It is an object of the invention to provide an improved machine for forming box blanks having blank-forming instrumentalities adjustable to form box blanks of different dimensions.

In the accomplishment of the above and in accordance with a feature of the invention the machine has cooperating punch and die assemblies, one of the assemblies being movable toward and away from the other, the assemblies having cooperating punches and dies for simultaneously removing material from opposite sides of a web of blank material to form a pair of corner laps for each of two successive blanks; the punches and dies being mounted on the respective assemblies for adjustment to vary the amount of material removed.

In producing a blank of the type described above creases are formed between the end wings and the body portion of the blank, between the corner laps and the side wings and between the end wings and end wing extensions, the creases facilitating bending of the various portions of the blank relatively to the other portions in forming the blank into a box. In accordance with a further feature of the invention the crease forming instrumentalities are mounted for adjustments relatively to one another and to the other blank-forming instrumentalities further to facilitate formation of box blanks of different dimensions.

The above and other features of the invention, including various details of construction and novel combinations of parts will now be described by reference to the drawings and pointed out in the claims.

In the drawings,

Fig. 1 is a schematic view of some of the operating parts of the machine illustrating the steps by which the web is transformed into discrete box blanks;

Fig. 2 is a plan view of a blank thus formed;

Fig. 3 is a side elevation partly in section of the machine;

2

Fig. 4 is an angular view illustrating portions of the punch and die assemblies of the machine;

Fig. 5 is a plan view of the die assembly;

Fig. 6 is a plan view of the punch assembly;

Fig. 7 is a section through the punch and die assemblies, this section being taken along the lines VII—VII of Figs. 5 and 6;

Fig. 8 is a side elevation, partly in section of the end wing extension creasers and the cutoff mechanism;

Fig. 9 is a detail view on a large scale of one set of the creasers illustrating their action on the work; and

Fig. 10 is an enlarged side elevation of the creased portion of the work after being operated upon by the mechanism shown in Figs. 8 and 9.

The invention is illustrated as embodied in a machine for forming box blanks of the type illustrated in Letters Patent of the United States 1,811,135, granted June 23, 1931, on an application filed in the name of C. D. Knowlton, although it will be understood that the operating instrumentalities of the machine may be modified to produce blanks of other forms. A blank 10 of the type produced by the machine is illustrated in Fig. 2 and is shown to comprise a body portion 12, side wings 14 separated from the body portion by creases 16, end wings 18 separated from the body portion by creases 20, corner laps 22 separated from the side wings by creases 24, and end wing extensions 26 separated from the end wings 18 by creases 28.

As illustrated in Fig. 1 the blanks are formed from a web of material 30 directed by guide plates 32 between upper and lower creaser rolls 34, 36, the web being fed by upper and lower feed rolls 38, 40. The creaser rolls 34, 36 are adjustably carried by shafts 42 (Fig. 3) and have cooperating ribs and grooves 44, 46 respectively, so that, as the web passes between the rolls, lengthwise creases are formed in the web which provide the creases 16 between the side wings 14 and body portion 12 in the finished blank.

Beyond the feed rolls 38, 40 in the direction of travel of the web is a punch and die mechanism 48 by which pieces of material are removed from each side of the web to form the corner laps 22 and slots 50 which separate the corner laps from the end wings 18. The punch and die mechanism 48 also include mechanism to be described which forms the transversely extending creases 24, 26 which separate the corner laps 22 and end wings 18 from the side wings 14 and body portions 12 of the blanks. Located beyond the punch and die mechanism in the direction of travel of the web is a cutoff and creasing

mechanism 52 which produces the creases 28 between the end wings 18 and the end wing extensions 26 and which severs the blanks at 54 from the web of material from which they are produced. The now completed discrete box blanks are ejected from the machine by discharge rolls 56, 58.

Mechanism for operating the feed rolls 38, 40 and 56, 58, as well as the blank forming instrumentalities is illustrated in Fig. 3. Carried by a pair of supporting legs 60 of the machine is a shaft 62 to which is secured a gear 64 meshing with a pinion 66 on a drive shaft 68. The shaft 68 is continuously rotated during the operation of the machine to rotate the shaft 62. Carried by the shaft 62 for angular adjustment relatively thereto is a crank disk 70 provided with slots 72 through which extend screws 74 carried by a disk (not shown) secured to the shaft whereby the crank disk may be secured in adjusted position on the shaft 62. The crank disk 70 is formed with a diametrically extending slot 76 in which is adjustably secured a block 78 carrying a crank pin 80. For adjusting the block 78, a screw 82 is threaded into the block, the screw being held against lengthwise movement relatively to the crank disk by a collar 83 secured thereto and journaled in a lug 84 carried by the crank disk, the collar having an annular groove (not shown) engaged by a pin 85 carried by the lug 84. By turning the screw 82 the block 78 is adjusted radially of the crank disk to vary the throw of the crank pin 80 upon rotation of the shaft 62.

The lower drive roll 40 is secured to a shaft 86 and fast on the shaft is a ratchet 88 engageable with the teeth of which is a pawl 90 carried by a disk 92 rotatable with respect to the shaft 86 and the roll 40. Connected to the crank pin 80 is an upwardly extending rack 94 having teeth engageable with a pinion 96 secured to the disk 92 for rotation therewith. Journaled on the shaft 86 is a plate 98 to which is secured a plate 100 arranged to maintain the rack in driving engagement with the pinion 96. Upon rotation of the shaft 62 in a counterclockwise direction the rack 94 is moved downwardly thus turning the pinion 96 in a clockwise direction. Because the disk 92 is moved with the pinion 96 the ratchet 88 is driven by the pawl 90 in a clockwise direction imparting similar movement to the lower feed roll 40. After the shaft 62 has turned through a predetermined angle, the direction of movement of the rack 94 is reversed and the pinion 96 is moved in a counterclockwise direction whereupon the pawl 90 slips over the teeth of the ratchet 88 so that for half of each revolution of the shaft 62 no motion is imparted to the lower feed roll 40. During this time that the feed roll is at rest the mechanisms 48, 52 are operated to form the box blanks. In order to insure immediate stoppage of the drive rolls 38, 40, upon reversal of movement of the rack 94, a lining 102 (Fig. 1) of a brake band 104 is yieldingly held, by a spring 106, in engagement with the end of the roll 40. This brake band exerts sufficient drag on the roll 40 to arrest movement of the roll at the time downward movement of the rack 94 ends. The upper feed roll 38 carries a gear 108 which meshes with a gear 110 on the lower feed roll 40 so that the feed rolls turn in unison. The upper feed roll is journaled on a shaft 112 carried by bearing plates 114 which are in turn carried by eccentrics 116 on a shaft 118 journaled at the upper end of a bearing housing 120. Connected to the shaft 118 is a handle 122 by which the shaft 118 may be turned

to lift the roll 38 slightly thereby facilitating initial threading of the web between the feed rolls 38, 40 or interruption of the feed of the web whenever desired.

Secured to the upper ends of the legs 60 is a base 124 to which is secured a support 126 for the lower portion or die assembly 131 (Fig. 5) of the punch and die mechanism 48 and for the lower elements of the cutoff and creasing mechanism 52. Extending upwardly from the base 124 are guide rods 128 for a vertically movable crosshead 130 carrying a support 132 for the upper portion or punch assembly 133 (Fig. 6) of the punch and die mechanism 48 and for the upper portion of the cutoff and creasing mechanism 52. The upper ends of the guide rods 128 are connected together by reinforcing straps 134. During that part of the cycle of operation of the machine in which the feed rolls 38, 40 are at rest, the blank-engaging elements carried by the support 132 are moved by the crosshead 130 into and out of cooperative relation with the elements carried by the support 126. For reciprocating the crosshead 130, the shaft 62 carries at each end thereof an eccentric 136 (only one of which is illustrated), each eccentric being surrounded by an eccentric strap 138 connected by an adjustable rod 140 and pivot pin 142 to the crosshead 130. A second shaft, not shown, is carried by the legs at the right end of the machine and is similarly connected to the right end of the crosshead 130, this latter shaft being connected by gearing including a gear 143 to the gear 64 on the shaft 62.

The gear 143 is secured to a shaft 144 which also carries a sprocket 146 connected by a sprocket chain 148 to a sprocket 150 on the shaft carrying the lower discharge roll 56. This roll is continually rotated during the operation of the machine in a clockwise direction, as viewed in Fig. 3. The upper discharge roll 58 is not driven but rests by gravity in contact with the upper surface of the right end of the web during the feeding of the web by the rolls 38, 40, thereby cooperating with the discharge roll 56 to feed the web or to discharge a blank after it has been severed from the end of the web. The roll 58 is carried by levers 152, only one of which is shown herein, pivoted at 154 and each having an arm 156 carrying at its outer end an adjustable screw 158 arranged for engagement by a portion of the support 132 during the descent of the crosshead 130. With the crosshead in its upper position the weight of the roll 58 maintains it in contact with the upper surface of the blank material but during the latter portion of the downward movement of the crosshead, when operations are being performed on the blank material, the levers 152 are moved in a counterclockwise direction by engagement of the support 132 with the screw 158, lifting the roll 58 and permitting the web to remain stationary while it is being operated upon. Upon upward movement of the crosshead the roll 58 moves downwardly into contact with the blank which has now been severed from the web and in cooperation with the roll 56 discharges the completed blank from the machine.

For cutting the web of blank material to form the ends of the corner laps 22 (Figs. 1 and 2) of successive blanks the die assembly 131 includes dies 160, 160a (Fig. 5) with which cooperate punches 162, 162a (Fig. 6) of the punch assembly 133 to form the end edges of the corner laps of the trailing end of the leading blank. Similar dies 164, 164a of the die assembly cooperate with punches 166, 166a of the punch as-

sembly to form the end edges of the leading corner laps of the succeeding blank. The die assembly carries creaser members 168, 168a with which cooperates a creaser member 170 of the punch assembly to form the creases which separate the corner laps from the side wings at the trailing end of the leading blank. The creaser member 170 cooperates with a creaser member 172 of the die assembly which is located between the creaser members 168, 168a to form the crease which separates the end wing from the body of the blank. The corresponding creases on the leading end of the succeeding blank are formed by creaser members 174, 174a, 176 of the die assembly and a creaser member 178 of the punch assembly.

For forming the slots 50 which separate the corner laps from the end wings and which define the side edges of the end wings, knives 180, 180a are carried by the punch assembly and cooperate with shear blocks 182, 182a of the die assembly, and with the adjacent surfaces of the dies 160, 160a, 164, 164a and a portion of the creaser members 168, 168a, 174, 174a, 172 and 176. The blocks 182, 182a are adjustably carried by the plates 186, 192 by screw and slot connections 183. Blocks 184 are located between the dies and the associated creaser members and their surfaces form a continuation of the surfaces of the dies with which the knives 180, 180a cooperate. The dies and punches by which the ends of the corner laps are formed are illustrated as of a shape to provide a saw tooth formation to the ends of the corner laps but it will be understood that they may be shaped as desired according to the type of box blank which is to be made by the machine.

Referring now to Figs. 5 and 7 the dies 160 and 164 are carried by a plate 186 secured to the support 126 for adjustment transversely of the direction of travel of the web of blank material. The plate 186 is provided with slots 188 through which pass screws 190 by which the plate is secured in its desired position relatively to the support. Similarly the dies 160a, 164a are carried by a plate 192 secured by screws 194 in the desired position transversely of the support 126. The undersurfaces of the plates 186, 192 are slotted to receive a bar 196 (Fig. 7) secured thereto, this bar being seated in a slot in the support 126 and determining the lengthwise position of the plates 186, 192 on the support 126.

By loosening the screws 190, 194 and moving the plates 186, 192 toward or away from each other the positions of the dies by which the ends of the corner laps are formed are adjusted transversely of the path of movement of the web, thus controlling the width of the body portion of the blank from which a box is to be subsequently formed. The dies 160, 160a, 164, 164a are provided with slots through which pass screws 198 to secure the dies to the plates 186, 192 in the desired positions along the path of movement of the web. These slots are narrower at the bottom than at the top thus forming shoulders against which the heads of the screws bear to clamp the dies in place. When the distance between the ends of the corner laps of adjacent blanks is to be varied for reasons to be described the screws 198 are loosened and the dies are moved relatively to their supporting plates.

The creaser members 172, 176 are provided with tongues 200 which fit into slots 202 formed in tie bars 204, which are located in ways 205.

in the upper surfaces of the plates 186, 192. Screws 206 passing through slots 207 assist in adjustably securing the plates 186, 192 and the tie bars together. The slots 202 cooperate with the tongues 200 to guide the creaser members 172, 176 when adjusted lengthwise of the direction of travel of the blank. Screws 208 pass through slots 210 in the tongues 200 and are threaded into the tie bars to clamp the creaser members in the proper positions of adjustment. The creaser members 168, 168a, 174, 174a are provided with tongues 212 having slots 214 through which the screws 215 pass thereby clamping the creaser members and the outer ends of the bars 204 to the plates 186, 192. The slots 214 permit adjustment of the creaser members lengthwise of the direction of travel of the blank and the slots 207, 216 in the bars 204 through which the screws 206, 215 pass permit adjustment of the plates 186, 192 and with them the corresponding creaser members 168, 168a, 174, 174a transversely of the direction of travel of the blank.

The blocks 184 between the creaser members 25 and the associated dies are held in positions by pins 218 which enter holes in the creaser members and the blocks. In order to change the lengths of the corner laps the distance between the effective portions of the creaser members and 30 of the dies must be varied. To form continuous surfaces for cooperation with the slotting knives 180, 180a the blocks 184 are replaced by blocks of the proper width. If the creaser members 172, 176 are adjusted toward or away from each other the shear blocks 182, 182a must be replaced by shear blocks of the proper lengths. Also if the width of the box to be formed from the blank is to be varied and the plates 186, 192 are to be moved toward or away from each 35 other for this purpose, the creaser members 172, 176 will be replaced by creaser members of the proper length.

The punch assembly is carried by a pair of plates 220, 222 (Fig. 6) similar to the plates 186, 192 and mounted for adjustment toward and from each other transversely of the direction of movement of the web of blank material on the support 132. The plates have slots 224 through which pass screws 226 threaded into the support 132 adjustably to secure the plates in position. Secured to the plates is a T-shaped bar 228 (Fig. 7) which fits in a correspondingly shaped slot 230 in the support and locates the plates lengthwise of the support 132. The punch members 162, 166a are generally U-shaped as shown in Fig. 6, the legs of the U being provided with slots 232 through which pass screws 234 threaded into guide bars 235 secured to the plates 220, 222 to hold the punches in the desired positions lengthwise of the direction of travel of the web. The punches have ways 237 (Fig. 4) which receive the guide bars 235 to locate the punches on the plates longitudinally of the direction of travel of the web. The punches 162a, 166 are provided with tongues 236 which fit into the recesses formed by the legs of the punches 166a, 162 respectively. The punches 162a, 166 are slotted to receive screws 238 by which the punches are secured in the desired positions on the plates 222, 220.

The knives 180, 180a are secured to blocks 240 which are mounted for adjustment relatively to the supporting plates 220, 222 transversely of the direction of movement of the web. For this purpose the blocks are provided with slots 242 through which pass screws 244. The undersur-

faces of the blocks 240 carry pads 246 of sponge rubber which cooperate with the shear blocks 182, 182a to insure separation of the web of blank material from the punch assembly upon upward movement of the punch assembly at the completion of a cycle of operation. To insure separation of the severed blank from the punch assembly sponge rubber blocks 248 are adjustably carried by the plates 220, 222 adjacent to the punches 166, 166a.

The creaser members 170, 178 are secured by screw-and-slot connections 250 to tie bars 252 which are in turn secured by screw-and-slot connections 254 to the plates 220, 222. The creaser members 170, 178 include creaser bars 256 which cooperate with grooves 258 formed in the corresponding creaser members of the die assembly, so that upon downward movement of the punch assembly the material in the blank is forced by the bars 256 into the grooves 258 in the lower creaser members to form creases about which the material of the blank is turned in the subsequent formation of the box.

In order to maintain the proper alignment of the punch and die assemblies during the operation of the machine the plates 186, 192 (Fig. 5) of the die assembly are provided with guide pins 260 which fit in holes 262 of plates 264 (Fig. 6) secured to the plates 220, 222 of the punch assembly. The pins 260 are carried by plates 266 secured to the plates 186, 192 of the die assembly. The guide pins insure that the plates 186, 192 will not shift on the support 126 relatively to the plates 220, 222 respectively of the punch assembly during the operation of the machine.

The creases 28 which separate the end wings and the end wing extensions of successive blanks (Fig. 1) are formed and the severing of successive blanks along the line 54 is accomplished by the cutoff and creasing mechanism 52 (Fig. 3). The lower portion of the cutoff and creasing mechanism is best illustrated in Figs. 5, 8 and 9. This portion of the mechanism is carried by a block 268 adjustably secured to the support 126 by screws 270 threaded into the support and passing through slots 272 in the block. For holding the block 268 against lateral displacement with respect to the support 126 the block fits in a recess 274 in the upper surface of the support. The right end of the block is provided with a guide plate 276 (Figs. 3 and 5) which serves to guide the end of the web when being initially fed into the machine over the top of the block 268.

The other end of the block is recessed at 280 and 282 to receive at opposite sides of the block creaser holders 284, 286 for creaser members 288, 290 extending transversely of the block in the recesses. The holders 284, 286 have depending legs provided with slots 292 through which pass screws 294 by which the supports are secured to the block 268 for vertical adjustment. The creaser members 288, 290 are shaped as illustrated in Fig. 8 and are held against adjacent inclined surfaces 296 of the holders 284, 286 by springs 298. These creaser members have tail pieces 300 which normally bear against the adjacent surfaces of the block 268 but it will be understood that when a downward force is exerted on the creaser members 288, 290 during the creasing operation the creaser members pivot in a counterclockwise direction as viewed in Fig. 8 against the actions of the springs 298 about the lower ends of the tail pieces 300 and thereby approach portions 302, 304 of the block 268 which form stationary creaser members. Located between

the creaser members 288, 290 and seated in a recess in the supporting block 266 is a shear block 306 secured in place by a screw 308 threaded through the left end of the block 268.

Cooperating with the creaser members and shear block just described are creaser blades 310, 312 and a knife 314 carried by a supporting block 316 adjustably secured by screws 318 to the support 132 (Fig. 6). The block 316 is provided with slots 320 through which the screws 318 pass thus permitting the block 316 to be adjusted in accordance with the position of the block 268. The creaser blades 310, 312 are received in slots in the block 316 and are held in place by set screws 322 (Figs. 6 and 8). The knife 314 is received in a slot 324 between the creaser blades 310, 312 and is yieldably held in place by a screw 326. This screw passes through a hole 328 in the outer end of the block 316 and is threaded into the block at 330. A sleeve 332 surrounds the screw 326 in the hole 328 and is held in engagement with the outer end of the knife 314 by a plurality of spring washers 334 which are not fully compressed. This arrangement permits the knife to yield slightly during its cutting action. It will be understood that the knife 314 cooperates with the shear block 306 to sever the blank simultaneously with the formation of the creases 28 between the end wings and the end wing extensions of the successive blanks.

The action of the creasers on the work is best illustrated in Figs. 9 and 10. Upon descent of the crosshead carrying the upper portion of the cutoff and creaser assembly, the creaser blade 310 forces the work between the creaser members 288 and 302 as shown in Fig. 9. The downward force exerted by the creaser blade on the work causes the creaser member 288 to pivot in a counterclockwise direction whereupon the material is pinched between the creaser members 288, 302 and the creaser blade 310 causing a separation of the laminae of which the web of blank material is formed. A crease formed in this manner is known as a "pinch" crease. Upon relief of pressure on the work by upward movement of the crosshead the material assumes the condition indicated in Fig. 10 at the crease line 28. It will be understood that in setting up the boxes from the blanks formed by this machine the end wing extensions are turned through an angle of approximately 180° whereas the corner laps and side wings and end wings are turned only through an angle of 90°. By operating on the material at the crease lines 28, as illustrated herein, the material is readily turned through an angle of 180° without danger of tearing the cover paper of the blank.

During the operation of the creaser blades 310, 312 and the knife 314 (Fig. 8) the web of blank material is held rearwardly of the line along which the completed blank is to be severed from the web of blank material. The work is clamped between the top surface of the shear block 306 and a clamping bar 340 yieldably carried by the block 316 between the knife 314 and the creaser blade 312. For thus supporting the bar 340 a pair of pins 342 are carried for vertical sliding movement in the block 316 and are provided with enlarged heads at their lower ends which are bifurcated to receive the ends of the bar 340 which are connected to the heads of the pins at 342. Springs 344 act between the heads of the pins and the block normally to force the pins and the clamping bar 340 downwardly to a position determined by the engagement of collars 346 with

the block 316. Upon descent of the crosshead, the clamping bar 340 engages the work prior to the engagement therewith by the knife 314 and the creaser blades 310, 312 and upon further downward movement of the crosshead the springs 344 yield whereupon the knife and the creaser bars move downwardly with respect to the clamping bar to form the creases 28 and to sever the completed blank from the web of blank material.

In adjusting the machine for the manufacture of box blanks of different sizes, the die assembly 131 with the lower part of the creasing and cut-off mechanism 52 is removed from the support 126 by removing the screws 190, 194 by which the supporting plates 186, 192 are secured to the base. It will be understood that the plates 186, 192 are rigidly connected at this time by the bars 204 so that the entire assembly is removable as a unit. In like manner the punch assembly 133 with the upper portion of the cutoff and creasing mechanism 52 is removed from the support 132 by removal of the screws 226 by which the plates 220, 222 are secured to the support. After removal from the machine the die assembly is placed on a bench and the punch assembly is placed upwise down on the bench so that the various operating instrumentalities are readily accessible for proper adjustment. Such adjustment as is required in the die assembly is made and corresponding adjustments are made in the punch assembly. Proper alinement of the punches 162, 166, etc., with the corresponding dies is readily made by placing the punch assembly on the die assembly after the dies have been properly adjusted and then moving the punches into engagement with the respective dies. Proper alinement of the parts will be maintained when the punch and die assemblies are again placed in the machine by the cooperation of the pins 260 with the apertures 262 (Fig. 6) in the plates 264.

The machine is designed for adjustment in accordance with variations in width, length or depth of the boxes to be formed, or in any two or more of these dimensions. Assume now that a change is to be made in the length of the blank because of a difference in the length of the box to be formed but that no change is to be made in the height of the box. The end wings 18 and the end wing extensions 26 will be of the same length but the length of the body portion 12 will be varied. Consequently, the overall length of the blank must be changed and this is accomplished by adjusting the position of the block 18 carrying the crank pin 80 thereby effecting a change in the amount of blank material fed during each cycle of operation of the machine. In order that the blanks be cut off at the proper location in accordance with the change in the lengths thereof, the cutoff and creasing mechanism 52 will be shifted lengthwise of the path of movement of the web of blank material. For this purpose the screws 270 (Fig. 5) and the screws 318 (Fig. 6) will be loosened and the positions of the blocks 268, 316 will be adjusted in accordance with the change in length of the box blanks.

Assume now that blanks are to be produced for a narrower box. Assuming that the height of the box is not to be changed it will be obvious that a narrower web of blank material will be required. The positions of the creaser rolls 34, 36 transversely of the path of movement of the web will be adjusted in any suitable manner so that the width of the body portion of the blank will correspond to the width of the box to be formed. In order that the slots 50 separating the corner laps

from the end wings and the positions of the corner laps be properly located in accordance with this decrease in width of the body portion of the blank, the plates 186 and 192 of the die assembly (Fig. 5) will be adjusted toward each other to decrease the space between the dies 160, 164 and the dies 160a, 164a. In order to permit this adjustment the creasers 172, 176 must be removed and replaced by creasers of the appropriate length. Similarly the plates 220, 222 (Fig. 6) of the punch assembly will be moved in accordance with the adjustment of the plates 186, 192 of the die assembly. However, no change is required in the creasers 170, 178 for this purpose since they do not interfere with the movement of the plates 220, 222 relative to each other.

Because of the decrease in width of the body portion of the blank the lengths of the corner laps must be decreased so that they will properly abut each other when the box is set up. Consequently the dies 160, 160a and the dies 164, 164a are adjusted in opposite directions lengthwise of the direction of travel of the web. To permit this adjustment the blocks 184 between the dies and the associated creasers will be removed and replaced by blocks of the proper widths. In like manner the punches 162, 162a, 166 and 166a will be adjusted lengthwise of the direction of travel of the web to correspond to the positions of the dies.

If now the height of the box is to be varied, assuming no change in the width of the box, the height of the side wings and end wings must be changed and a web of the proper width must of course be fed through the machine. By running a web of the proper width the height of the side wings is automatically taken care of. Because of the necessity of changing the lengths of the end wings the overall lengths of the blanks must be varied which is done by adjusting the position of the crank pin 80 (Fig. 3). It is necessary if the length of the box is not to be changed that the difference in the length of the blank be accounted for solely by the length of the end wings. Consequently the positions of the dies 160, 160a with their creasers 168, 168a relative to the positions of the dies 164, 164a with their respective creasers 174, 174a lengthwise of the machine must be varied. This is done by adjusting as a unit each die, creaser and spacing block lengthwise of the machine, as required. The creasers 172, 176 must of course be adjusted in accordance with the change in positions of the other creasers and to permit this adjustment the shear blocks 182, 182a will be removed from the machine and replaced by shear blocks of the proper lengths. Corresponding adjustments will be made in the punch assembly (Fig. 6), the knives 180, 180a with their supporting blocks 240 being replaced by blocks and knives of the proper lengths.

It will be understood that by a combination of the adjustments described above any two or more dimensions of the blanks to provide boxes of different sizes may be made.

In the operation of the machine, during each revolution of the drive shaft 62 the web is fed to the right, as viewed in Fig. 3, a distance equal to the total overall length of the blank, and the web then comes to rest while the crosshead 130 moves downwardly, cutting off one blank along the line 54 (Fig. 1) and simultaneously forming the creases 28 between the end wings and end wing extensions. At the same time the corner laps and slots separating the corner laps from the

end wings at the trailing end of one blank and the leading end of the next succeeding blank are formed by the punch and die mechanism 48, the creases 20, 24 separating the end wings and corner laps from the body portion of the blank and the side wings respectively being simultaneously formed.

Having thus described the invention, what I claim as new and desire to secure by Letters Patent of the United States is:

1. In a machine for forming box blanks from a web of blank material, means for feeding the web, cooperating punch and die assemblies, one of said assemblies being movable toward and away from the other, said assemblies including cooperating punches and dies for simultaneously removing material from opposite sides of the web to form a pair of corner laps for each of two successive blanks, said punches and dies each including a pair of members relatively adjustable to vary the amount of material removed thereby, means mounting said punches and dies for adjustments laterally of the path of movement of the web through the machine to vary the distance between the corner laps at opposite sides of the blank being formed, and means for varying the amount of feed of the web between successive operations thereon by said punch and die assemblies.

2. In a machine for forming box blanks from a traveling web of blank material, cooperating punch and die assemblies, one of said assemblies being movable toward and away from the other, said assemblies including cooperating punches and dies for simultaneously removing material from opposite sides of the web to form a pair of corner laps for each of two successive blanks, said punches and dies each including a pair of members relatively adjustable to vary the amount of material removed thereby, means mounting said punches and dies for adjustments laterally of the path of movement of the web through the machine to vary the distance between the corner laps at opposite sides of the blank being formed, and members adjustable with said punches and dies for forming creases at the bases of the corner laps.

3. In a machine for forming box blanks from a traveling web of blank material, cooperating punch and die assemblies, one of said assemblies being movable toward and away from the other, said assemblies including cooperating punches and dies for simultaneously removing material from opposite sides of the web to form a pair of corner laps for each of two successive blanks, said punches and dies each including a pair of members relatively adjustable to vary the amount of material removed thereby, means mounting said punches and dies for adjustments laterally of the path of movement of the web through the machine to vary the distance between the corner laps at opposite sides of the blank being formed, members adjustable with said punches and dies for forming creases at the bases of the corner laps, and means mounting said last-named members for adjustment relatively to said punches and dies to vary the lengths of the corner laps.

4. In a machine for forming box blanks from a traveling web of blank material, a die assembly comprising a pair of supporting plates movable toward and away from each other transversely of the path of movement of the web, tie bars for securing said plates together in adjusted positions, creaser members carried by said tie bars

for adjustment relatively thereto along the path of movement of the web, dies carried by said plates inwardly of said creaser members for adjustment relatively to said plates and to said creaser members along the path of movement of the web, and means cooperating with said die assembly for forming the corner laps of a box blank.

5. In a machine for forming box blanks from a traveling web of blank material, a punch assembly comprising a pair of supporting plates movable toward and away from each other transversely of the path of movement of the web, tie bars for securing said plates together in adjusted positions, creaser members carried by said tie bars for adjustment relatively thereto along the path of movement of the web, punches carried by said plates inwardly of said creaser members for adjustment relatively to said plates and creaser members, knives carried by said plates, said knives extending between said creaser members and mounted for adjustment transversely of the path of movement of the web, said knives being arranged to form slots between the end wings and corner laps of the box blanks, and means cooperating with said punch assembly for forming the corner laps and end wings of a box blank.

6. In a machine for forming box blanks from a traveling web of blank material, a punch assembly comprising a pair of supporting plates movable toward and away from each other transversely of the path of movement of the web, tie bars for securing said plates together in adjusted positions, creaser members carried by said tie bars for adjustment relatively thereto along the path of movement of the web, punches carried by said plates inwardly of said creaser members for adjustment relatively to said plates and creaser members, knives carried by said plates, said knives extending between said creaser members and mounted for adjustment transversely of the path of movement of the web, said knives being arranged to form slots between the end wings and corner laps of the box blanks, means cooperating with said punch assembly for forming the corner laps and end wings of a box blank, said means comprising a die assembly including a pair of supporting plates movable toward and away from each other transversely of the path of movement of the web, tie bars for securing said last named plates together in adjusted positions, creaser members adjustably carried by said last named tie bars cooperating with the creaser members of the punch assembly, dies adjustably carried by said last named plates and cooperating with the punches of the punch assembly, and shear blocks extending between the creaser members at opposite sides of the die assembly between said dies, said shear blocks and dies cooperating with said knives in the formation of the slots between the end wings and corner laps.

7. In a machine for forming box blanks from a traveling web of blank material, a punch assembly comprising a pair of supporting plates movable toward and away from each other transversely of the path of movement of the web, tie bars for securing said plates together in adjusted positions, creaser members carried by said tie bars for adjustment relatively thereto along the path of movement of the web, punches carried by said plates inwardly of said creaser members for adjustment relatively to said plates and creaser members, knives carried by said plates, said knives extending between said creaser mem-

bers and being mounted for adjustment transversely of the path of movement of the web, said knives being arranged to form slots between the end wings and corner laps of the box blanks, means cooperating with said punch assembly for forming the corner laps and end wings of a box blank, and other mechanism adjustable lengthwise of the path of movement of the web for completing the formation of the blank, said mechanism including creaser members constructed and arranged to form pinch creases extending transversely of the end wings to form end wing extensions.

GEORGE S. SILLARS.
